UNITED STATES PATENT OFFICE.

THOMAS CLARK AND IVAN VLASTO, OF STOCKTON HEATH, ENGLAND.

ELECTRICAL SWITCH.

No. 913,810.

Specification of Letters Patent.

Patented March 2, 1909.

Application filed December 14, 1907. Serial No. 406,403.

To all whom it may concern:

Be it known that we, THOMAS CLARK and IVAN VLASTO, subjects of the King of England, residing at Stockton Heath, in the county of Chester, England, have invented new and useful Improvements in or Connected with Electrical Switches, of which the following is a specification.

This invention has reference to electric switches adapted to be used as controllers for starting purposes—say motors, or for controlling motor speeds and similar purposes; and it has among other things, for its objects and effects, to provide an arrangement of resistance which gives a magnetic blow-out at all contacts, thereby protecting such contacts; to provide generally an arrangement which is convenient and more mechanical than starting switches as at present employed, and would stand very severe usage; also to provide one wherein no "live" parts are exposed, besides being water-tight; and further to provide an arrangement or construction by which all connections from the resistances to the contacts are avoided.

The invention has further reference to overload and no-voltage releases connected with starting or controlling switches.

The invention will be described with the aid of the accompanying drawings, which illustrate it.

In these drawings, Figure 1 is an elevation in section of an electric switch; Fig. 2 is a detail section; Fig. 3 is an outside plan; and Fig. 4 is a plan with the top plate removed, showing the internal arrangement of same. Fig. 5 is a front elevation; and Fig. 6 is a plan of the carrier for the wipers, and showing the position of the blow-out pole face. Fig. 7 is a diagrammatic view illustrating the switch apparatus.

In a controller or starting switch for motors, and electrical installations of an analogous or equivalent nature, the resistances are arranged so as to provide a magnetic field at all contacts where the circuit is broken, so as to blow out the arc formed by breaking the circuit, and so protecting the contacts, and dispensing with separate coils to accomplish this. These resistance coils are wound alternatively right and left hand, so as to oppose each other magnetically, to give a magnetic field in the air-gap between a central cylinder comprising the resistances and contacts, and an iron or steel bar, placed in front of same.

In all the different figures, the same or equivalent parts are marked with the same figures of reference, wherever they occur in the drawings.

Referring now to the drawings, 1 are the resistance coils of the switch, and 2 are the contact bosses or rings, having upon their periphery copper partial rings 3, with a gap between the ends which come opposite to the wipers 4 in the "off" position (see Fig. 4). The contact bosses 2 are mounted round a central spindle 4, which has a flat part or side, as shown in Fig. 4, for keeping the bosses in their right position; and they—the rings—70 are insulated from the spindle, by a sheathing of insulation 6, and washers 7 at the upper and lower ends.

The resistances consist of coils made of a strip of metal, bent on edge, with an insulation 8 between the convolutions; they being connected at their upper and lower ends with the contact bosses 2, and each resistance is mounted between two of these contacts. By this form of resistance, the heat generated 75 is conducted to the outside through the metal, thereby facilitating the dissipation of heat; also giving an additional advantage, when the coils are mounted between the contacts on the cylinder, of dispensing with all 85 connection from the resistance to the contacts.

The spindle 4 is mounted at one end in an upper cover or plate 10, and its lower end in a base plate or bottom 11; and the whole of 90 the parts are inclosed within a cylindrical casing 12 extending between the cover and bottom, 10, 11; and the cylinder 12 has an angle ring 13 at the top and bottom, to which it is suitably fastened. The cylinder and 95 rings are split longitudinally; and one half is provided with a hinge at 14 upon which it can be swung, and access to the interior gained; the other half of the case being a fixture.

Air ducts 15 are provided in the inside of the contact bosses 2, so that air has free access to the interior of the resistance coils 1; and by these means convection of heat from the inside of the coils is assisted. And the 105 bosses are also constructed, as clearly shown in Figs. 1 and 4, so that the air can enter and leave at every one, and so produce or provide free ventilation. Ventilation apertures are also provided in the upper plate or 110 cover 10, as shown by Fig. 3.

All the contact bosses 2 and resistance coils

1 are bound up against a shoulder or collar 16 at the bottom of the spindle 4, by a nut 17 screwed on its upper end.

- The parts which are to make contact with 5 the contacts 2 consist of bent metal wipers 20, these being carried by flexible or spring strips 21 from a main carrier bar or standard 22, fixed to the upper and lower plates 10, 11. This bar is insulated from the upper plate 10, 10 and from the lowermost wiper strip 21 by insulation 23, the part of the bar or frame carrying this lowermost strip being also insulated at its lower end from the bottom plate or base 11.
- 15 The carrier standard or bar 22 besides supporting the wipers 20, also electrically connects them, so that when the coil cylinder is turned, and the contacts 2 of the same touch their respective wipers in rotating, the resistance coils are cut out in the same rotation.

Of course, the gaps between the ends of the contact strips 3 will be so disposed in series, in relation to each other, to give the 25 consecutive action of the resistance coils required.

The resistance coils 1 as above stated, are wound alternately right and left hand, so as to oppose each other magnetically, to give a 30 magnetic field in the air gap between the central cylinder, (comprising the contacts and coils) and an iron or steel bar 5—covered with asbestos or the like—carried from the wiper carriers, placed in the front of same, 35 as shown more particularly in Figs. 4, 5, and 6. By these arrangements and provisions, a magnetic field is provided at all contacts where the circuit is broken, and the arc formed by breaking the circuit is blown out, 40 and the contacts protected.

The whole coil cylinder is rotated by a handle 25 fixed on the upper end of the spindle 4.

In the diagram, 30 represents the main 45 supply and return conductors, 31 the motor armature, 32 the shunt coils, 33 the over-load release, and 34 the no-voltage release.

What is claimed is:—

1. In an electric starting and controlling 50 switch, a spindle having a plurality of spaced contact strips, a plurality of resistance coils, wherein each alternate coil is wound in an opposite direction to the other coils, connected to and arranged between the said 55 strips; and means operating as an electric blow out.
2. In an electric starting and controlling 60 switch, a spindle having a plurality of spaced contact strips provided with ventilating 80 apertures; a plurality of resistance coils wherein each alternate coil is wound in an opposite direction to the other coils, con-

nected to and arranged between the said strips; and means operating as an electric blow out.

3. In an electric starting and controlling switch, a spindle having a plurality of spaced contact strips having ventilating spaces; a plurality of alternately wound resistance coils having means for conducting the heat 70 away from the coils, and connected to and mounted between the said strips; and means operating as an electric blow out.

4. In an electric starting and controlling switch, a spindle having a plurality of spaced 75 and ventilated contact strips, a plurality of resistance coils disposed between the contact strips and connected therewith, each coil being composed of alternate coils of wire and thin metal rings, the coils between alternate 80 strips being wound in opposite directions; and means operating as an electric blow out.

5. In an electric starting and controlling switch, a spindle having a plurality of alternately arranged ventilated contact strips and 85 resistance coils, adjacent members of the coils being wound in opposite directions; and means for constituting a magnetic field about the contact strips capable of operating as an electric blow out.

6. In an electric starting and controlling switch, a spindle having a plurality of alternately arranged ventilated contact strips and oppositely wound adjacent resistance coils having means for conducting the heat away 95 from the coils, and an electric blow out arrangement, comprising an insulated iron or steel bar arranged adjacently to the resistance coils for constituting a magnetic field about the contact strips.

7. An electric starting and controlling switch, comprising a spindle having a plurality of alternately arranged ventilated contact strips and resistance coils, the latter having interposed metal rings for conducting the 105 heat away, while adjacent members are oppositely wound; an iron bar inclosed in an insulating casing of asbestos, and arranged adjacently to the resistance coils, and constituting in conjunction with the said coils a 110 magnetic field which operates as an electric blow out; and a casing, comprising a metal cylinder mounted between end plates, half of such casing operating as a hinged door for gaining access to the parts of the switch.

In testimony whereof we have signed our names to this specification in the presence of two subscribing witnesses.

THOMAS CLARK.
IVAN VLASTO.
